WAVE MOTOR DEVICE

Charles A. Webber, Brooklyn, N. Y.

Application November 11, 1931, Serial No. 574,293

5 Claims. (Cl. 253—11)

This invention relates to wave motor devices and has for its object the provision of a wave motor device which is adapted to be operated with a minimum degree of wave motion.

5 Another object of the present invention is to provide a wave motor device adapted to produce a continuous flow of power without the necessity of providing means to store the wave motor energy.

10 Another object of the present invention is to provide a simple, efficient and inexpensive wave motor device.

Other objects and advantages will become apparent as the invention is more fully disclosed.

15 In accordance with the objects of the present invention I have devised an assembly of elements comprising the wave motor device in which a fulcrumed arm is supported upon a suitable pier or wharf extending out over the water from the 20 shore-line a suitable distance; the short end of the arm extending out over the water and the longer end thereof extending shoreward. A float element is attached to the shorter lever arm and the other end of the lever is adapted to operate 25 suitable air or water pumping mechanism with a vertical rise and fall of the lever, the effluent of said pump mechanism being conveyed away to operate power generating apparatus; all as will be more fully hereinafter disclosed.

30 Before further disclosing the nature and scope of the present invention reference should be made to the accompanying drawings, wherein

Fig. 1 illustrates one modification of the present invention;

35 Fig. 2 illustrates a second modification thereof; and

Fig. 3 illustrates a contemplated improvement of Fig. 2.

Referring to the drawings, the fulcrum lever 40 arm 1 having a fulcrum point 2 positioned upon the end of pier or wharf 3 carries upon the short end 4 thereof a float 5. The other arm of fulcrum lever 1 (identified by numeral 1) extends shoreward a distance several times that of the 45 length of arm 4. With this arrangement of fulcrum lever arms a relatively small vertical movement in lever arm 4 resolves itself into a relatively large vertical movement at the end of long arm 1. This movement may be utilized in the generating 50 of power. One of the most simple ways of adapting this vertical movement or displacement of the longer arm of the lever to the generating of power is to adapt it first to the pumping of water and thereafter utilize the water in the generating 55 of power in any convenient manner heretofore

employed in the art. Other means effecting substantially the same power generating result may be utilized, if desired.

As a specific embodiment of the present invention I will disclose the apparatus devised to apply 60 this vertical movement in the pumping of water which in turn is to be used in the generating of power. I am not to be limited thereby to the specific embodiment as the broader methods of application of this vertical movement of the lever 65 arm are contemplated by me.

The end of the lever arm is slotted as indicated at 6 and is provided with a bar 7 adapted to roll freely in the slot 6. The slotted end of the lever is positioned between vertical parallel bars 8. 70 Small lever arms 9 are positioned upon the parallel bar 8 substantially as shown with the shorter arm thereof adapted to be engaged by the bar 7 upon a vertical movement of the lever arm 1. The long arm of levers 9 are attached to one end 75 of a rope or cable 10 running over pulley 11; the other end of rope 10 being attached to pump arm 12.

In the specific embodiment shown when the fulcrum lever 1 is actuated by a rise and fall of 80 float 5 the end of the long arm engages by means of bar 7 one or more of the fulcrum arms 9, thus exerting a downward pull on the end of cable 10 thereby raising up pump handle 12. Weight 13 is provided on the end of the pump handle 12 to 85 return the handle to its initial position when a reverse movement in the fulcrum lever arm 1 is obtained. As a result of this cycle, pump 14 is actuated and water flows therefrom into inclined 90 trough or channel 15 from whence it is conveyed to power generating means.

Whereas I have shown a single fulcrumed lever attached to a float, I may equally as well employ a plurality of fulcrumed levers attached to a single large float, each longer lever arm being adapted 95 to energize mechanism adapted to generate power as is illustrated in the modification disclosed in Figs. 2 and 3.

In Figs. 2 and 3, identical parts are identified by the identical numerals applied to the parts 100 in Fig. 1. The ends of the short arms of a plurality of fulcrumed lever arms 1 are fixedly positioned at spaced intervals to float 5 each individually functioning in the pumping of water substantially in the same manner as hereinbefore 105 described with respect to the apparatus of Fig. 1.

In Fig. 3, the ends of the short arms of the plurality of lever arms are grouped in the manner illustrated through a common fulcrum point.

To provide for a rise and fall in tide a plurality 110

of fulcrumed lever arms 9 are provided. These may be spaced apart any convenient distance depending upon the particular tide conditions where the apparatus is installed.

5. It is also believed apparent that the specific relative position of vertical parallel bars 8 with respect to end of lever arm 1 may also be varied widely without departing essentially from the present invention depending upon the wave height 10 existing at the point of installation of the wave motor device.

The relative lengths of the lever arms may also be widely varied depending upon the conditions existing at the point of installation and upon the 15 desired amount of motion necessary to operate pump 14.

The weights of float 5, lever arm 1 and weight 13 must be adjusted relative to each other for efficient results, the specific adjustments obviously 20 depending upon conditions at the point of installation.

It is believed clear from the above description, taken in connection with the drawings that the wave motor device of the present invention is 25 adapted to be operated under conditions where there is a minimum wave height and therefore singularly free from periods of inactivity due to periods of calm or wave inactivity. Heretofore in the art wave motor devices have been dependent upon a relatively large rise and fall of the waves at the point of installation. In periods of calm the efficiencies of these prior art wave motor devices have fallen. In the present invention periods of calm will have relatively little effect 30 upon the efficiency of the wave motor device and the device may be installed in places where the average rise and fall of the wave is relatively low and where the same may be protected from the unusual conditions incident to storms, floods and the like. Moreover, it is believed clear from the 35 above description and drawings that the wave motor device of the present invention is operative irrespective of variations in the tide level of the body of water and also operative with substantial equal efficiency at any given wave height and through a relatively wide range of varying wave heights. The general adaptability and utility of the present invention thereby is greatly enlarged.

Having with particularity broadly and specifically disclosed the present invention, it is apparent that many modifications and departures may be made therein without departing essentially from the nature and scope thereof as may be set forth in the following claims.

55. What I claim is:

1. A wave motor device comprising a fulcrumed lever having a short arm and a long arm, means to support the said lever with the short arm extending out over water, a float element rigidly attached to the end of said short lever arm and means to translate the vertical rise and fall of said long lever arm incident to wave motion acting upon said float to the generation of power irrespective of variations in the tide level of said water and with substantial equal efficiency at any given wave height.

2. A wave motor device comprising a plurality of fulcrumed levers each having a short arm and a long arm, means to support said levers with the

short arm extending out over water, a float element rigidly attached to the ends of said short lever arm, and means to translate the vertical rise and fall of said long lever arms incident to wave motion acting upon said float to the generation of power irrespective of variations in the tide level of said water and with substantial equal efficiency at any given wave height.

3. In a wave motor device of the type described and claimed in claim 1, wave motion translating means comprising a pair of standards positioned vertically adjacent the end of the longer lever arm and on opposite sides thereof, a cross bar attached to said long lever arm and extending at right angles thereto a distance beyond the said standards, said cross bar being adapted to be longitudinally movable along the said long lever arm end and to ride vertically along the said standards and a plurality of fulcrumed levers positioned in vertical spaced relation upon the said standards 90 with the arms thereof extending in a plane parallel to the said long lever arm in a position adapting one of the arms of said plurality of levers to be intercepted by the said cross bar as it is vertically displaced along the said standard by a rise 100 and fall of said long lever arm and means to operatively connect the opposite arms of said plurality of levers to power generating means.

4. In a wave motor device of the type described and claimed in claim 2, wave motion translating means comprising a pair of standards positioned vertically adjacent the end of each long lever arm and on opposite sides thereof, a cross bar attached to each long lever arm and extending at right angles thereto a distance beyond the said 110 standards, said cross bar being adapted to be longitudinally movable along the said lever arm end and to ride vertically along the said standards, and a plurality of fulcrumed levers positioned in vertical spaced relation upon each of the said 115 standards with the arms thereof extending in a plane parallel to the said long lever arms and in a position adapting one of the arms of said plurality of levers to be intercepted by the said cross bar as it is vertically displaced along the said 120 standard by a rise and fall of said long lever arm and means to operatively connect the opposite arms of said plurality of levers to power generating means.

5. In a wave motor device comprising a fulcrumed lever supported out over the water with the shorter arm thereof attached to a float element adapted to rise and fall with the wave motion of said water, means adjacent the end of the longer arm to utilize the vertical movement of 130 said arm in the generation of power, said means comprising a roller element positioned in a slot in the end of said longer lever arm and adapted to ride therein against the side of a vertically extending support, a plurality of fulcrumed levers 135 positioned on said support and disposed in spaced relationship thereon the full potential vertical displacement distance of the longer lever arm due to tide variations, one arm of said levers being positioned so as to be engaged by said roller, and 140 the other arm thereof being adapted to energize the power generating apparatus.

CHARLES A. WEBBER.

70. A wave motor device comprising a pair of standards positioned vertically adjacent the end of each long lever arm and on opposite sides thereof, a cross bar attached to each long lever arm and extending at right angles thereto a distance beyond the said standards, said cross bar being adapted to be longitudinally movable along the said long lever arm end and to ride vertically along the said standards and a plurality of fulcrumed levers positioned in vertical spaced relation upon each of the said standards with the arms thereof extending in a plane parallel to the said long lever arms and in a position adapting one of the arms of said plurality of levers to be intercepted by the said cross bar as it is vertically displaced along the said standard by a rise and fall of said long lever arm and means to operatively connect the opposite arms of said plurality of levers to power generating means.

75. A wave motor device comprising a pair of standards positioned vertically adjacent the end of each long lever arm and on opposite sides thereof, a cross bar attached to each long lever arm and extending at right angles thereto a distance beyond the said standards, said cross bar being adapted to be longitudinally movable along the said long lever arm end and to ride vertically along the said standards and a plurality of fulcrumed levers positioned in vertical spaced relation upon each of the said standards with the arms thereof extending in a plane parallel to the said long lever arms and in a position adapting one of the arms of said plurality of levers to be intercepted by the said cross bar as it is vertically displaced along the said standard by a rise and fall of said long lever arm and means to operatively connect the opposite arms of said plurality of levers to power generating means.
